UNITED STATES PATENT OFFICE.

JOSEPH E. LEONARD AND GEORGE H. ILTEN, OF CEDAR RAPIDS, IOWA.

OVEN.

1,161,232.

Specification of Letters Patent. Patented Nov. 23, 1915.

Application filed May 10, 1915. Serial No. 26,984.

To all whom it may concern:

Be it known that we, JOSEPH E. LEONARD and GEORGE H. ILTEN, citizens of the United States, residing at Cedar Rapids, in the county of Linn and State of Iowa, have invented certain new and useful Improvements in Ovens; and we do hereby declare the following to be a full, clear, and exact description of the invention, such as will enable others skilled in the art to which it appertains to make and use the same.

This invention relates to stoves and ranges, and more particularly to the construction of the oven therefor.

The object of the invention is to improve the oven and facilitate the assembling of the parts thereof by a novel construction of the face-plate and side-plates and the connections therefor, whereby the face-plate may be securely attached to the side-plates by a bolt at each corner, thereby dispensing with a great many bolts which were formerly required.

The invention is fully disclosed in the description and claims following, reference being had to the accompanying drawings, in which—

Figure 1 is a front elevation of an oven embodying our invention. Fig. 2 is a section of one corner of the same in the line *a b* of Figs. 1, 3 and 4. Fig. 3 is a top view of the corner clamping plate. Fig. 4 is a bottom view of one corner of the front-plate. Fig. 5 is a view in perspective of a corner of one of the side-plates.

In the drawing, 1 denotes an elevated oven communicating by a flue 2 with the combustion chamber of a stove below, not shown. The oven is provided with doubled walls 3 and 4 at the sides, bottom and top, the space between the walls being for the products of combustion to pass around the inner enclosure and thus heat the oven, in a manner that need not be particularly described.

These walls, above referred to as side-plates, may connect directly with a back-plate (not shown) in a simple and convenient way, but at the front they must connect with a rectangular frame 5, above referred to as the front-plate. Hitherto it has been the practice to attach the front-plate, which carries the hinged door 6, by means of rod-bolts passing from the front to the back of the oven between the side-plates, or by bolting the front-plate to flanges of the side-plates. To make a tight joint the latter required a

good many bolts, while in the former case the rods were exposed to the destructive heat from the combustion chamber.

The improved device for connecting the front and side-plates will now be described. The front plate 5, as will be seen, is provided with channels 7 and 8 to receive the edges of the side-plates 3 and 4, respectively. Between them, at each corner, are bolt-holes 9 to receive stove-bolts 10. The whole front edge of each side-plate entirely around the oven is folded at an angle, as shown at 8 in Figs. 2 and 5, these folds being made before the sheets are bent at the corners. The angle of the fold conforms to that of the channel into which it is to fit, a perfectly tight joint being secured by the use of "stove-putty", in a well known way. Bridging the space between the channels 7 and 8 at the corners are clamp-plates 11, having angled terminals 12 and 13 fitting nicely into the angles of the side-plates, respectively. These clamp-plates have holes coinciding with those in the corners of the front-plate, to receive stove-bolts, and on the under (inner) side have lugs 14 to hold the nuts 15 from turning. In assembling the oven, it is placed on its back, the front plate 5 is laid in position on top, and the clamp-plates, with nuts in position, are successively placed in position, there being holes (not shown) in the outer side-plates to admit the operator's hand, and the bolts inserted and screwed tight. The front-plate is thus securely and tightly held in place, and at the expenditure of little time and effort.

Having thus described our invention, we claim:

1. The combination with the front and side-plates of an oven, of a clamp-plate connecting the inner and outer side-plates, and a bolt connecting said front-plate and clamp-plate.

2. The combination with the front and angled side-plates of an oven, of a clamp-plate bridging the space between the inner and outer side-plates, and conforming to their respective angles at the corner, a connection of each end of the clamp-plate with its respective side-plate corner, and a member connecting the clamp and front-plates.

3. The combination of a front-plate for an oven, channeled for inner and outer side-plates, side-plates folded on the front edges to conform with the said channels, clamp-plates with angled ends fitting the angles of

said folded edges, and a member connecting the same with the front-plate.

4. A connection for the front and side-plates of an oven, comprising a front-plate
5 channeled for inner and outer side-plates, side-plates folded at an angle along the front edges, clamp-plates having ends conforming to the respective fold-angles at the corners, and bridging from the inner to the outer
10 plate, and connecting members for connect-

ing said clamp and front-plates at the corners.

In testimony whereof we affix our signatures in presence of two witnesses.

JOSEPH E. LEONARD.
GEO. H. ILTEN.
